United States Patent Office

Des. 229,033
Patented Nov. 6, 1973

229,033

UTILITY CLIP

F. Wayne Cooper, Anaheim, Calif.
(1749 South 50 West, Bountiful, Utah 84010)

Filed Jan. 3, 1972, Ser. No. 215,280

Term of patent 14 years

Int. Cl. D8—08

U.S. Cl. D8—259

Fig. 1.

Fig. 2.

Fig. 3.

FIG. 1 is a perspective view of a utility clip, showing my new design looking in the direction of the top, front, and left side thereof;

FIG. 2 is a rear elevation view thereof; and

FIG. 3 is a right side elevation view thereof.

The bottom surface, not shown, is the same in appearance as the top surface.

I claim:

The ornamental design for a utility clip, as shown and described.
